UNITED STATES PATENT OFFICE.

CHARLES H. CLARK, OF DORMONT, AND HOWARD L. BEACH, OF EDGEWOOD, PENNSYLVANIA.

TILTING SIDE-DUMP CAR.

1,333,293.

Specification of Letters Patent.

Patented Mar. 9, 1920.

Application filed October 11, 1916. Serial No. 124,986.

To all whom it may concern:

Be it known that we, CHARLES H. CLARK, a citizen of the United States, and resident of Dormont, in the county of Allegheny and State of Pennsylvania, and HOWARD L. BEACH, a citizen of the United States, and resident of Edgewood, in the county of Allegheny and State of Pennsylvania, have invented certain new and useful Improvements in Tilting Side-Dump Cars, of which the following is a specification.

This invention relates to dump cars of the general type disclosed in patents to Charles H. Clark, No. 1,007,533, October 31, 1911, and Nos. 1,182,643 and 1,182,644, May 9, 1916, and the primary object is to improve and simplify the mechanism for transmitting opening and closing movements to the doors. This feature of the invention is embodied in means mounted on the tilting car body and so connected to the door and to the under frame that movement of the body relative to the under frame will impart positive movement to the door so that as the body begins to tilt the door on the dumping side begins to open. When body has reached its extreme tilt the door has reached its extreme opening and as the body is moved back toward its horizontal position the door is proportionally moved toward its closed position.

The doors extend from end to end of the body and constitute the side walls thereof when the body is upright, the door at the lowering side being adapted to turn outwardly and downwardly when the car is dumped and form a chute-like extension for directing the discharging load clear of the track. As each door extends from end to end of the body the mechanism for transmitting motion thereto is repeated or duplicated at such intervals as is necessary to positively control the movement of the door, thereby forestalling the effect of unequal strains on different portions of the door and sufficiently reinforcing all portions thereof to withstand the stress placed thereon whether the same be equally or unequally distributed. In constructions of prior design the several devices for transmitting motion to the door have been so connected thereto that sluggish or irregular movement of one mechanism would affect all the other mechanisms. In the present invention this

difficulty has been overcome by so arranging the several mechanisms that each operates independently of the rest excepting in so far as all are mounted on the car body and positively actuated by the movement of the latter relative to the under frame.

While the invention has particular reference to a car that is adapted to dump at either side of the track, the operating mechanisms for each door are quite distinct from the mechanisms for operating the other door, said mechanisms being of such design that they operate to open and close the door at the dumping side only, the mechanisms at the opposite side retaining their normal door-locking position during the dumping operation. While such mechanisms are ordinarily sufficient to retain the door at the rising side in closed position, a further feature is the provision of a lock which is separate and distinct from the door actuating mechanisms, and which is so arranged that when one door is unlocked for dumping the opposite door is necessarily locked.

The arrangement is such that the door actuating mechanisms at the rising side of the body are adapted to be released from the under frame and permit said mechanisms to rise with the body without being moved from door-locking position, such releasing mechanism also constituting the primary means for so releasing the body from the under frame as to enable it to rock in the desired direction. The releasing devices are mounted on shafts which extend longitudinally of the car in order that the several actuating mechanisms for the same door may be either secured or released simultaneously. Heretofore, these shafts have been extended through the under frame bolsters and to the ends of the car for connection with levers or other operating devices. When a car is in service there is unavoidable slight relative movement on the shafts and bolsters which is sufficient to cause the shafts to bind or to otherwise impair their operation. In the present invention this difficulty has been overcome by locating the latch-carrying shafts wholly between the under-frame bolsters, and providing relatively short shafts which are loosely connected to the latch-carrying shafts and which extend through the bolsters to the car

end for receiving the operating levers, whereby the latch-carrying shafts are permanently retained in operative position.

In the accompanying drawings, Figure 1 is a side elevation of a portion of a side dump car constructed in accordance with the invention. Fig. 2 is a view of the car partly in end elevation and partly in cross-section, the plane of the portion in section being indicated by line 2-2 of Fig. 1. Fig. 3 is a cross-section on line 3-3 of Fig. 1. In Figs. 2 and 3 the dumping position of the car body is shown in dotted lines. Fig. 4 is a detail view of a portion of the door actuating mechanism when door is closed. Fig. 5 is a detail side elevation of a bracket secured to the car underframe and to which the actuating mechanism is operatively connected. Fig. 6 is a detail view of the same parts shown in Fig. 4 but as positioned when car body is tilted and door is opened. Fig. 7 is an enlarged side elevation of the connection between the operating shaft and the latch actuating shaft.

Referring to the drawings, the under frame which may be of any preferred construction is here shown as consisting of a central box girder which extends from end to end of the car, the separated channel beams 2 comprising the side of the girder and plate 3 the top thereof. At each end of the car the under frame includes a bolster 4 preferably arranged centrally of the truck, and the top of the bolster is constructed with the toothed or cogged rocker-receiving surface 5. At each end of the under frame is the upstanding fixed end frame 6 and at the outer side of the latter a platform 7.

The car body consists of a frame which carries floor 8, end walls 9 and the door-forming side walls 10, the latter hinged at 11 to the frame to turn outwardly and downwardly in continuation of floor 8 for discharging the load clear of the track, as shown in dotted lines in Figs. 2 and 3. A desirable construction of the body frame consists of a centrally located beam 12 and the opposite side beams 13. At suitable intervals are the vertical transversely disposed diaphragms 14. At each end of the body frame is a rocker 15 which is adapted to fit and coöperate with the rocker supporting face 5 of bolster 4, in the preferred adaptation the arrangement being such that the body is adapted to rock toward either side for dumping. The under frame being without side sills the body is carried quite low, with a resulting low center of gravity for the car, without interfering with freely inclining the body toward either side when dumping.

The motion transmitting mechanisms for the doors are located wholly beneath the body, the absence of side sills affording ample room therefor at each side of the

central girder to which said mechanisms are operatively connected at such intervals throughout the length of the door as may be necessary. Each of said mechanisms consists primarily of a bell-crank lever 16 fulcrumed at 17 to the under portion of the body frame between two separated diaphragms 14, Fig. 1. In normal position, i.e., with the body upright, the shorter arm of the lever is disposed downwardly while the longer arm extends outwardly toward the door to which it is connected by link 18. Link 18 is pivoted at 19 to lever 16 and at 19' to arm 20 depending from the door. When the body is upright pivot connection 19 is slightly beneath a line extending between points 17 and 19', forming a toggle construction with link 18 and lever 16 provided with the upwardly abutting stops 21, lever 16 and link 18 securely hold the door in closed position as in Fig. 2.

Pivoted at 17' to the depending arm of the bell-crank 16 are links 22 which are connected by pin 23 to a link 24, pivoted at 24' to the upper portion of the bifurcated upstanding bracket 25 secured to channel beam 2 of the under frame. At the lower outer side of the bracket is the pad or bearing surface 26 against which the lower extremity of link 24 is adapted to bear and against which it is held by the engagement of pins 23 by latch hooks 27. These hooks are fixedly mounted on shaft 28 which extends from bolster to bolster and is journaled in bearings 25' in brackets 25. It is apparent that when the car body is rocked to the horizontal position the side door and link mechanism on the high, non-dumping side will thrust pins 23 downwardly and links 24 will guide them into position where they may be engaged by latch hooks 27.

As best shown in Figs. 3 and 7, secured to each end of shaft 28 is a crank 28' connected by a link 29 to a crank 30' on the inner end of an operating shaft 30. Shaft 30 extends from the end frame of the car through the bolster and is operated by an actuating lever 31 accessible at the end of the car. With the parts thus arranged, shafts 28 terminate at the inner sides of bolster 4 and are in no way affected by relative movement of the bolster and shaft as might result if said shafts were continued through the bolster. Link 29 is slotted at 29' where it connects with crank 28', so that shaft 28 may be operated by shaft 30 at either end of the car without moving the corresponding shaft 30 at the opposite end. Shafts 28 are cross connected by the tension device 32 secured to arms 32', whereby the opposite latches are normally held under tension in positive engagement with pins 23, thereby locking the body securely in upright position while in transit.

Operation: The first step is to release latches 27 from pins 23 on the non-dumping

side of the car as shown on the left hand side of Fig. 2, so that when the body is tilted to the position shown by dotted lines in Figs. 2 and 3 the link mechanism attached to the non-dumping side will rise with the body and maintain its door locking position.

On the dumping side the downward movement of the body breaks the toggle 17, 19, 19' and at the extreme tilt the link mechanism assumes the position shown in Fig. 6. The raising of toggle pin 19 to this position causes the door to open on hinge pin 11 to the position shown. When the body is returned to normal position the reversed movement of the link mechanism closes the door.

As heretofore noted, the motion transmitting mechanisms are arranged at such intervals throughout the length of the door as may be necessary, and it is further characteristic of the construction that each of said mechanisms operates independently of the other mechanisms excepting as all are affected and controlled by the movement of the body, with the result that any undue deflection or other disturbing influence that may even slightly affect one of said mechanisms will have no effect on the others.

While the motion transmitting mechanism will be ordinarily sufficient to hold the door at the rising side securely locked as in dotted lines in Fig. 2, to guard against any possibility of the joint being sprung between levers 16 and link 18, a lock is provided at the end of the car for positively securing the door at the rising side. As here embodied the lock consists of a hook-like pivoted latch 40 for each door adapted to engage pin 41 thereon. The opposite latches are connected by rod 42 with the result that when the latch is in position to release the door at the dumping side the other latch is necessarily in door locking position, as shown in Fig. 2.

Mechanism for rocking the body during the dumping operation comprises no portion of the present invention. The same may be variously embodied, for instance as disclosed in any of the above mentioned patents to Charles H. Clark.

50 We claim:

1. In a side dump car, an under frame, a body mounted thereon for tilting toward either side, downwardly opening doors for opposite sides of the body, a series of independently operating door actuating devices suspended from and adapted to move with the body, connections between each of said devices and the door operated by said series, and means connecting each of said devices with the under frame in such manner that the series of devices for actuating the door at the rising side of the body are rendered inoperative during dumping operation.

2. In a side dump car, the combination of

an under frame, a body mounted thereon for tilting toward either side, downwardly opening doors for opposite sides of the body, a series of actuating mechanisms of like construction for each door, each mechanism consisting of a bell-crank lever fulcrumed to the body, an operative connection between the lever and the door, connecting means interposed between the lever and the under frame, and a series of latches for detachably locking said connecting means in position to actuate the door.

3. In a side dump car, the combination of an under frame, a body mounted thereon for tilting toward either side, downwardly opening doors for opposite sides of the body, a series of actuating mechanisms of like construction for each door, each mechanism consisting of a bell-crank lever fulcrumed to the body, an operative connection between the lever and the door, connecting means interposed between the lever and the under frame, and a guiding device extending from the frame to said connecting means for directing the latter in its movement relative to the under frame.

4. In a side dump car, the combination of an under frame, a body mounted thereon for tilting toward either side, downwardly opening doors for opposite sides of the body, a series of actuating mechanisms of like construction for each door, each mechanism consisting of a bell-crank lever fulcrumed to the body, an operative connection between the lever and the door, two links jointed together with one link pivotally connected to said lever and the other to the under frame, and means for securing the links to the under frame at the point where they are jointed together.

5. In a side dump car, the combination of an under frame, a body mounted thereon for tilting toward either side, doors for opposite sides of the body, and actuating mechanisms of like construction for the doors, each mechanism consisting of a lever fulcrumed to the body, an operative connection between the lever and the door, two links jointed together with one link pivotally connected to said lever and the other link pivoted to and adapted to turn downwardly on the under frame, the under frame having a bearing surface for the jointed connections between the links, and releasable means for securing the links to said bearing.

6. In a side dump car, the combination of an under frame, a body mounted thereon for tilting toward either side, doors for opposite sides of the body, and actuating mechanisms of like construction for the doors, each mechanism consisting of a lever fulcrumed to the body, an operative connection between the lever and the door, a link pivotally secured at one end of said lever, a transversely disposed pin carried by the link, latch devices

movably mounted on the under frame for detachably engaging said pin, and means for guiding the pin-carrying link toward and from position to be engaged by the latches.

5 7. In a side dump car, the combination of an under frame, a body mounted thereon for tilting toward either side, downwardly opening doors for opposite sides of the body, a series of actuating mechanisms of like 10 construction for the doors, each mechanism consisting of a bell-crank lever fulcrumed to the body, an operative connection between the lever and the door, links jointed together on a transverse pin with one link pivotally 15 connected to said lever and the other link pivotally connected to the under frame and constituting a guide for the first mentioned link, and latch means mounted on the under frame for detachably securing thereto said 20 link connecting pin.

8. In a side dump car, the combination of an under frame, upright brackets secured to opposite sides of the frame, each bracket having a bearing surface and above the latter a bearing for an operating part, a body mounted on the under frame to tilt toward either side, doors for opposite sides of the body, and actuating mechanisms of like construction for each door, each mechanism 25 consisting of a lever fulcrumed to the body, an operative connection between the lever and the door, two links jointed together with one link pivoted to said lever and the other link rotatably mounted in the bearing of the 30 appropriate frame supported bracket, the joint between the links adapted to bear against said surface, and releasable means for holding the link joint to said surface.

9. In a side dump car, the combination of 40 an under frame, a body adapted to tilt thereon, a downwardly opening door for the lowering side of the body, a lever fulcrumed to the body, a link pivotally connected to the lever and to the door, said pivotal connections and the lever fulcrum being arranged 45 with relation to each other so as to hold the door in closed position when the body is upright, and an operative connection between the lever and the under frame for causing 50 the lever to open and close the door with a definite relation to the position of the body during movements of the body relative to the under frame.

10. In a side dump car, the combination 55 of an under frame, a body mounted to tilt thereon toward either side, downwardly opening doors for opposite sides of the body, a series of actuating mechanisms of like construction for each door, each mechanism 60 consisting of a bell-crank lever fulcrumed to the body, a link pivotally connected to the lever and to the door with said pivotal connections and the lever fulcrum arranged to hold the door in closed position when the 65 body is upright and when the lever is free

to move with the body without turning on its fulcrum, a link pivotally connected to the lever and extending toward the under frame, and releasable means for preventing movement of said link.

11. In a dump car, an underframe, a body mounted thereon and adapted to be tilted to one side thereof, a door on that side of the body adapted to be opened and closed and a plurality of independent mechanisms, each 75 connected to said door and to said underframe, and adapted to open said door when said body is tilted.

12. In a dump car, an underframe, a tilting body mounted thereon and provided 80 with hinged doors, independent mechanisms mounted on said body and adapted to be actuated by relative movement of said body and said underframe and, when so actuated, to swing said doors on the latters' hinges. 85

13. In a dump car, the combination of an under frame, a body mounted to tilt on the frame transversely thereof for dumping at the side of the car, a door hinged to the lowering side of the body when the latter is 90 tilted and adapted to open outwardly and downwardly, and a plurality of independently operating door actuating mechanisms spaced apart lengthwise of the door with each mechanism operatively connected to 95 the door and pivoted to the underframe and constructed so that tilting movement of the body operates to move the door through each mechanism independently of the other mechanisms.

14. In a dump car, the combination of an underframe, a body mounted to tilt on the frame transversely thereof for dumping at the side of the car, an outwardly and downwardly opening hinged door for the lowering side of the body, a plurality of independently operating door actuating devices spaced apart lengthwise of the door with each device mounted on the body, and operatively connected to said door and to said 105 underframe so that tilting movement of the body operates said door through each of said devices.

15. In a dump car, the combination of an underframe, a body mounted to tilt thereon, 115 an outwardly and downwardly opening door for the lowering side of the body, a plurality of identical independently operating door actuating devices spaced apart lengthwise of the door with each device pivoted to 120 the body and with the pivots of the several devices in line with each other, an operative connection between each of said devices and the door and an operative connection between each of said devices pivoted to the under frame and constructed so that tilting movement of the body operates said door through each of said pivoted devices. 125

16. In a dump car, the combination of an underframe, a body mounted to tilt on the 130

frame transversely thereof for dumping at the side of the car, the body extending laterally beyond the underframe, an outwardly and downwardly opening door for the lowering side of the body, a plurality of identically independently operating door actuating devices spaced apart lengthwise of the door and mounted on the body, an operative connection between each of said devices and the door, and an operative connection between each of said devices pivoted to the underframe and constructed so that tilting movement of the body operates said door through each of said devices.

15 17. In a dump car, the combination of an under frame, a body mounted to tilt thereon for dumping at the side of the car, an outwardly and downwardly opening door for the lowering side of the body, the 20 under portion of the body provided with transverse diaphragms, a plurality of door actuating devices spaced apart lengthwise of the door with each device pivotally secured to adjacent diaphragms and adapted 25 to operate therebetween, an operative connection between each of said devices and the door, and an operative connection between each of said devices and the under frame, whereby tilting movement of the body 30 transmits movement to the door through each of said devices.

18. In a dump car, the combination of an under frame, a body mounted to tilt thereon for dumping at either side of the 35 car, an outwardly and downwardly opening door carried by each side of the body, devices at either side of the under frame connected thereto and also connected to the body and releasable means for restraining 40 the body from tilting toward the opposite side of the frame, and operative connections between said devices at either side of the frame and the correspondingly located door for actuating the door at the dumping side 45 of the body.

19. In a side dump car, the combination of an under frame, bolsters adjacent opposite ends of the under frame, a body mounted to rock on the bolsters, a door for the 50 lowering side of the body, motion transmitting mechanism mounted on the body and operatively connected to the door, a shaft extending longitudinally of the under frame between and terminating at the bolsters, releasable means mounted on such 55 shaft for holding the motion transmitting mechanism against operation, and an operating shaft connected to said first mentioned shaft and extending to the end of 60 the car.

20. In a side dump car, the combination of an under frame, bolsters for the frame adjacent opposite ends thereof, a body mounted to rock on the under frame toward either side, doors for opposite sides of 65

the body, motion transmitting mechanism for each door mounted on the body and operatively connected to the door, shafts extending longitudinally of and rotatably supported by the under frame with such 70 shafts located between the bolsters, releasable means mounted on the shafts for securing the door actuating mechanisms against operation, and operating shafts connected to the first mentioned shafts and 75 transversing the bolsters and extending to the ends of the car.

21. In a side dump car, the combination of an under frame, a body mounted thereon to tilt toward either side, doors for opposite sides of the body, actuating means for each door mounted on the body and operatively connected to the door, releasable latch devices rotatably mounted on opposite sides of the under frame for securing the respective door actuating mechanisms against operation, and a tension device connecting the latch devices for opposing movement to either latch device in a direction to release the door actuating 90 mechanism secured thereby.

22. In a side dump car, an under frame, a tilting body mounted thereon, downwardly opening doors for opposite sides of the body, and independent mechanisms 95 pivoted to each of said doors and to the under frame and so constructed and arranged that as the body tilts, the door on the lowering side will be positively opened in exact accordance with the position of the 100 body and will be positively held against movement not in synchronism with the movements of the body.

23. In a side dump car, an under frame, a body mounted thereon for tilting toward either side, downwardly opening doors for opposite sides of the body, independent door opening and closing devices pivoted to the doors and to the under frame and each including means constructed and arranged to 105 cause the door on the lowering side to be positively opened while lowering and positively closed while raising in exact accordance with the position of the body and to be positively held against movement not in 110 synchronism with the body movements.

24. In a side dump car, an under frame, a body mounted thereon for tilting toward either side, downwardly swinging doors for opposite sides of the body, door opening 120 and closing means connecting with each door and the under frame and each including a bell-crank lever pivotally connected to the body for causing the door on the lowering side to open synchronously with 125 the body movement and in exact accordance with the position of the body and constructed so as to positively hold the door against movement not in synchronism with the movements of the body.

25. In a side dump car, an under frame, a body mounted thereon for tilting toward either side, downwardly swinging doors for opposite sides of the body, door opening and closing means for each door, each means comprising a series of links connected to the under frame, and door and a bell-crank lever connected to the body, and a latch for holding the door opening and

closing means on the lowering side of the 10 car in door opening and closing relation.

In testimony whereof we affix our signatures in presence of two witnesses.

CHARLES H. CLARK.
HOWARD L. BEACH.
